(57) **CLAIM**

The ornamental design for a hat as shown and described.

DESCRIPTION

FIG. 1 is a front view of a first embodiment of a hat showing my new design;

FIG. 2 is a rear view thereof;

FIG. 3 is a top plan view thereof;

FIG. 4 is a bottom plan view thereof;

FIG. 5 is a right side view thereof;

FIG. 6 is a left view thereof;

FIG. 7 is a sectional view thereof taken along line 7-7 in FIG. 3;

FIG. 8 is a sectional view thereof taken along line 8-8 in FIG. 3;

FIG. 9 is a front view of a second embodiment of a hat showing my new design;

FIG. 10 is a rear view thereof;

FIG. 11 is a top plan view thereof;

FIG. 12 is a bottom plan view thereof;

FIG. 13 is a right side view thereof;

FIG. 14 is a left view thereof;

FIG. 15 is a sectional view thereof taken along line 15-15 in FIG. 11; and,

FIG. 16 is a sectional view thereof taken along line 16-16 in FIG. 11.

The dashed broken line showing of the hat is for the purpose of illustrating portions of the article, and the dot-dash broken line defines the bounds of the claimed design. The dashed broken line and the dot-dash broken line form no part of the claimed design.
